(57) **CLAIM**

The ornamental design for a fire column, as shown and described.

DESCRIPTION

FIG. 1 is a perspective view of a fire column showing the new design.

FIG. 2 is a perspective view of a fire column showing another environment of use.

FIG. 3 is a front view of the design shown in FIG. 1.

FIG. 4 is a left-side view of the design shown in FIG. 1.

FIG. 5 is a right-side view of the design shown in FIG. 1

FIG. 6 is a back view of the design shown in FIG. 1.

FIG. 7 is a top view of the design shown in FIG. 1; and,

FIG. 8 is a bottom view of the design shown in FIG. 1.

The broken lines indicate unclaimed portions of the article and form no part of the claimed design.

1 Claim, 8 Drawing Sheets(56)
